APPARATUS FOR APPLYING METAL CASES
TO BRICKS

Clair I. Young, Pittsburgh, Pa., assignor to Harbinson-Walker Refractories Company, Pittsburgh, Pa., a corporation of Pennsylvania

Application June 9, 1947, Serial No. 753,583

15 Claims. (Cl. 18—1)

1 This invention relates to apparatus for applying metal cases to bricks.

In certain instances refractory bricks for industrial furnaces are partly enclosed in individual metal cases. Such bricks are made of non-acid refractory material such as magnesite, spinel, chrome ore, olivine, or a mixture of these and usually are not fired before being laid up. The high temperature of the furnace fires the bricks and causes adjoining metal cases to fuse with one another and with the bricks, whereby an integral structure is formed. The most common type of case is made from sheet metal bent into the form of a channel. Before application to a brick, the flanges of the case converge toward their free edges so that they will have to be sprung apart in order to permit a refractory brick to be inserted between them. When the flanges are released, they spring inwardly and tightly grip the brick, thereby holding the brick and case together.

It is among the objects of this invention to provide apparatus for spreading such cases open mechanically so that they can be applied to refractory bricks, which automatically feeds successive cases into brick-receiving position, which automatically inserts successive bricks in the cases, and which can be associated with a brick press so that the brick are cased automatically as they leave the press.

In accordance with this invention, a pair of substantially parallel tracks are provided for supporting the lower edges of the downwardly extending flanges of a channel shape sheet metal case. The tracks project a short distance up into the case and are spaced apart farther than the upper portions of its flanges so that the flanges will be sprung outwardly into downwardly diverging position. Means are provided for pushing a case lengthwise onto the tracks, and other means are adapted to lift a brick up between the diverging flanges and high enough to lift the case out of engagement with the tracks, whereupon the flanges will spring inwardly against the sides of the block and the encased block then can be lowered between the tracks. The tracks preferably are mounted on the side walls of a box which has an open end and bottom. The box may be provided with vertically movable means for normally holding a case down on the tracks, but which is capable of being pushed upwardly by the case when a block is elevated into it. The box also may be provided with means that will insure centering the case between the tracks when the flanges are released from them. It is pre-

ferred to feed the cases, one at a time, from the bottom of a stack disposed in a hopper. With such an arrangement, the bottom of the hopper is connected to the parallel tracks mentioned above by diverging tracks which gradually spread the case flanges apart as the case is pushed toward the parallel tracks. Most suitably, the cases are pushed out of the hopper by fluid pressure operated means, and fluid pressure may be used for raising the bricks into the cases whose flanges have been spread apart. By mounting this apparatus on the front of a brick press, the bricks formed in the press can be pushed directly onto the brick-lifting means and then lifted into the channels above it.

The preferred embodiment of the invention is illustrated in the accompanying drawings in which Fig. 1 is a fragmentary front view of a brick press with my casing apparatus attached to it; Fig. 2 is a horizontal section taken on the line II—II of Fig. 1; Fig. 3 is a vertical section taken on the line III—III of Fig. 1; Fig. 4 is an end view showing a brick inserted in a case and ready to be lowered; and Fig. 5 is a vertical section taken on the line V—V of Fig. 1.

Referring to the drawings, the major part of my casing apparatus is connected to a conventional refractory brick press by a large bracket. The bracket is formed from a long metal bar 130 extending across the front of the press, to the side frames 2 of which it is bolted, and a shorter horizontal bar 3 welded to the first bar by a pair of vertical triangular plates 4. This bracket supports a box-like housing 6 in front of the center of the press and just far enough above the level of the press table 7 to permit a brick 8 to be moved beneath the housing. The housing has a top plate 9 bolted to bar 3 above it and to a pair of depending side plates 10.

Bolted against the inner surfaces of the side plates along their lower edges are parallel rails 12 adapted to support the lower edges of the downwardly extending flanges 13 of a channel shape sheet metal case which is to be applied to a brick made in the press. As shown in Fig. 3, the tracks thus formed are spaced apart farther than the upper portions of the case flanges, and extend a short distance up into the case to spring the flanges out into downwardly diverging position. The distance between the upper portions of the flanges is substantially the same as the width of the brick, but the flanges initially converge downwardly, as shown in Fig. 5, so that a brick can not be inserted between them without first spreading them apart.

The empty case is held down on the tracks by means of a plurality of rollers 15 journaled in a hold-down plate 16. The rollers roll against the top of the case as it is pushed into one end of the housing. The hold-down plate is pressed downwardly by coil springs 17 encircling headed studs 18 slidably mounted in the top of the housing. For a purpose to be described later, the side plates of the housing are provided immediately above the tracks with openings therethrough in each of which slides a cup-like centering member 20 having a pointed inner end that engages the adjoining flange of the case, as shown in Fig. 3. Disposed in each of these members and compressed between it and a cap 21 welded to the outside of the adjoining side plate is a coil spring 22 which urges the centering member inwardly.

In order to move a case into the position shown in Fig. 3, it is pushed into one end of the housing and along the tracks. To enable this to be done easily, a horizontal cover plate 25, about as long as a case, is supported by the right-hand end of bracket bar 3 and has depending side flanges that support a pair of side plates 26 extending from the adjacent ends of housing side plates 18 to a point beyond the cover plate and the side of the press. The lower surface of the cover plate lies in the lower plane of the hold-down member in the housing. Fastened against the inner surfaces of side plates 26 near their lower edges are rails 27, the tops of which are adapted to support the lower edges of the case flanges. Secured to the inner surfaces of the rails are a pair of metal strips 28 standing on edge and extending a short distance above the rails, whereby tracks are formed for the cases. The front ends of these tracks are in alignment with the parallel tracks in the housing, but the metal strips and the tops of rails 27 converge as they extend away from the housing until they reach a point below the right-hand end of cover plate 25. From this point rearwardly the strips are parallel and close enough together to permit the converging flanges of a case to fit down over them and rest on the rails supporting the strips. Extending upwardly above these narrower parallel sections of the track is a hopper 29 of any desired height and of a size and shape to receive a stack of the metal cases, each having its flanges resting on the case below as shown in Fig. 1.

For feeding cases from the hopper to housing 6, a slide 31 is slidably mounted in grooves extending lengthwise of the inner surfaces of the two rails 27. The front end of this slide is rigidly connected by a bracket 32 to the front end of a piston rod 33 projecting from a fluid pressure cylinder 34 attached to the front of the press by means of a bracket 36. The rear end of the slide supports a pusher having an upright front member 37 from the top of which a horizontal plate 38 extends rearwardly. This plate forms a table on which the stack of cases can rest when the pusher pushes the bottom case out from under the stack, thereby preventing a case from dropping down behind the upright member.

Assuming that the pusher is in its retracted position in which the upright member 37 will be located directly behind the bottom case resting on parallel rails 27 in the hopper, the apparatus is started in operation by admitting fluid pressure to the rear end of the cylinder 34 in order to move slide 31 and the pusher forward. The front of the pusher slides the bottom case in the stack from the hopper and along the diverging tracks where the flanges of the case are progres-

sively sprung farther apart. The case is held down on the tracks by cover plate 25 against which the top of the case slides. As this case leaves the hopper, the remaining cases in the stack drop down on the table portion of the pusher where they are supported until the pusher is retracted by admitting fluid pressure to the front end of the cylinder. Then the lower case in the stack drops down in front of the pusher. 5 When the pusher again moves forward, this second case that it pushes out of the hopper pushes the case that was left on the diverging tracks forward along the parallel tracks 12 in housing 6, while the second case moves along the diverging tracks where it is left while the pusher moves back preparatory to moving the third case forward.

Before the third case is pushed out of the hopper, a refractory brick is elevated into the first case now located in the housing with its flanges spread apart as shown Fig. 3. This is accomplished by a lifting plate 41 mounted on the upper end of a piston rod 42 extending down into a fluid pressure cylinder 43 attached to the front of the press. The plate is guided by pins 44 extending down through bushings 46 also connected to the front of the press. In its lower position, the top of this plate is on a level with the press table so that when a brick is ejected 20 from the press and slid across the table it will be received by the plate directly below housing 6. Fluid pressure then is admitted to the lower end of cylinder 43 in order to raise the plate with the brick on it. The brick is lifted up between tracks 12 and rises high enough in the housing to engage the top of the case and raise the hold-down member against the resistance of springs 17. This withdraws the case flanges 13 from the tracks, and the flanges immediately spring inwardly 25 against the opposite sides of the brick to the position shown in Fig. 4. The centering members 20 follow the flanges and insure that the cased brick will be centered between the sides of the housing so that when plate 41 is lowered by the release 30 of pressure from cylinder 43, the encased brick 45 will descend with the plate between the parallel tracks.

When the next brick is ejected from the press it pushes the encased brick off plate 41 and onto 50 a slide 47. In the meantime, the second empty case has been pushed into the empty housing 6 by the case behind it. This operation of first moving a case into the housing and then lifting a brick into the case is repeated as long as desired, it being understood that it is timed with the operation of the press so that each successive brick ejected from the press is provided with a metal case. The timing can be effected in any suitable manner, such as by a cam (not shown), 55 actuated by the moving parts of the press, which controls the valves that control the flow of fluid under pressure to and from cylinders 34 and 43.

According to the provisions of the patent statutes, I have explained the principle and construction of my invention and have illustrated and described what I now consider to represent its best embodiment. However, I desire to have it understood that, within the scope of the appended claims, the invention may be practiced otherwise 60 than as specifically illustrated and described.

I claim:

1. Apparatus for applying a channel shape sheet metal case with downwardly extending flanges to a refractory brick that is wider than the space 75 between the lower edges of the flanges, compris-

ing a pair of substantially parallel tracks adapted to support the lower edges of the flanges of such a case and to project a short distance up into it, said tracks being spaced apart farther than the upper portions of the case flanges, means for pushing a case lengthwise onto said tracks to spring the case flanges outwardly into downwardly diverging position, and means adapted to lift a refractory brick up between the diverging flanges high enough to lift them out of engagement with said tracks, whereby the flanges will spring inwardly against the sides of the brick and the encased brick can be lowered between the tracks.

2. Apparatus for applying a channel shape sheet metal case with downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, means for pushing a case lengthwise onto said tracks to spring the case flanges outwardly into downwardly diverging position, vertically movable means for normally holding a case down on said tracks, and means adapted to lift a refractory brick up between the diverging flanges high enough to raise said vertically movable means and to lift the case out of engagement with said tracks, whereby the case flanges will spring inwardly against the sides of the brick and the encased brick can be lowered between the tracks.

3. Apparatus for applying a channel shape sheet metal case with downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, means for pushing a case lengthwise onto said tracks to spring the case flanges outwardly into downwardly diverging position, a vertically movable hold-down member adapted to rest on top of a case on said tracks, resilient means pressing said member downwardly, and means adapted to lift a refractory brick up between the diverging flanges high enough to raise said member and to lift the case out of engagement with said tracks, whereby the case flanges will spring inwardly against the sides of the brick and the encased brick can be lowered between the tracks.

4. Apparatus for applying a channel shape sheet metal case with downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, means for pushing a case lengthwise onto said tracks to spring the case flanges outwardly into downwardly diverging position, means adapted to lift a refractory brick up between the diverging flanges high enough to lift them out of engagement with said tracks, whereby the flanges will spring inwardly against the sides of the brick and the encased brick can be lowered between the tracks, and means adapted to center the case between the tracks when said flanges are released therefrom.

5. Apparatus for applying a channel shape sheet metal case with downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, means for pushing a case lengthwise onto said tracks to spring the case flanges outwardly into downwardly diverging position, means adapted to lift a refractory brick up between the diverging flanges high enough to lift them out of engagement with said tracks, whereby the flanges will spring inwardly against the sides of the brick and the encased brick can be lowered between the tracks, and spring biased means disposed above the tracks and adapted to engage the outer surfaces of the flanges of a case to center it between the tracks when said flanges are released from the tracks.

6. Apparatus for applying a channel shape sheet metal case with downwardly extending flanges to a refractory brick that is wider than the space between the lower edges of the flanges, comprising a housing provided with substantially parallel side walls and an open end and bottom, a pair of tracks in the housing mounted on the lower portions of its side walls and adapted to support the lower edges of the flanges of a case and to project a short distance up into it, said tracks being spaced apart farther than the upper portions of the case flanges, means for pushing a case lengthwise into said open end of the housing and along said tracks to spring the case flanges outwardly into downwardly diverging position, and means adapted to lift a refractory brick up between the diverging flanges high enough to lift them out of engagement with said tracks, whereby the flanges will spring inwardly against the sides of the brick and the encased brick can be lowered between the tracks to remove it from the housing.

7. Apparatus for applying a channel shape sheet metal case with downwardly extending flanges to a refractory brick that is wider than the space between the lower edges of the flanges, comprising a box provided with substantially parallel side walls and an open end and bottom, a pair of tracks in the box mounted on the lower portions of its side walls and adapted to support the lower edges of the flanges of a case and to project a short distance up into it, said tracks being spaced apart farther than the upper portions of the case flanges, means for pushing a case lengthwise into said open end of the box and along said tracks to spring the case flanges outwardly into downwardly diverging position, a vertically movable hold-down member disposed in the upper part of the box and adapted to engage the top of a case on said tracks, resilient means above said member for pressing it downwardly, and means adapted to lift a refractory brick up between the diverging flanges high enough to raise said member and to lift the case out of engagement with said tracks, whereby the case flanges will spring inwardly against the sides of the brick and the encased brick can be lowered between the tracks to remove it from the box.

8. Apparatus for applying a channel shape sheet metal case with downwardly extending flanges to a refractory brick that is wider than the space between the lower edges of the flanges, comprising a box provided with substantially parallel side walls and an open end and bottom, a pair of

tracks in the box mounted on the lower portions of its side walls and adapted to support the lower edges of the flanges of a case and to project a short distance up into it, said tracks being spaced apart farther than the upper portions of the case flanges, means for pushing a case lengthwise into said open end of the box and along said tracks to spring the case flanges outwardly into downwardly diverging position, means adapted to lift a refractory brick up between the diverging flanges high enough to lift them out of engagement with said tracks, whereby the flanges will spring inwardly against the sides of the brick and the encased brick can be lowered between the tracks, and resilient means inside the box connected to its side walls above said tracks and adapted to be compressed by said diverging flanges, said resilient means expanding and centering the case between the side walls when the case flanges are released from the tracks.

9. Apparatus for applying a channel shape sheet metal case downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, means at one end of said tracks for receiving a case, means for pushing the case from said receiving means lengthwise onto said tracks to spring the case flanges outwardly into downwardly diverging position, and means adapted to lift a refractory brick up between the diverging flanges high enough to lift them out of engagement with said tracks, whereby the flanges will spring inwardly against the sides of the brick and the encased brick can be lowered between the tracks.

10. Apparatus for applying a channel shape sheet metal case with downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, means spaced from one end of said tracks for receiving a case, means for pushing the case from said receiving means lengthwise onto said tracks to spring the case flanges outwardly into downwardly diverging position, guide tracks adapted to engage the inside of the case flanges and support their lower edges, the guide tracks diverging from said case-receiving means to said parallel tracks so as to gradually spread the case flanges apart as they are moved toward the parallel tracks, and means adapted to lift a refractory brick up between the diverging case flanges high enough to lift them out of engagement with said parallel tracks, whereby the flanges will spring inwardly against the sides of the brick and the encased brick can be lowered between the tracks.

11. Apparatus for applying a channel shape sheet metal case with downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, means for pushing a case lengthwise onto said tracks to spring the case flanges outwardly into down-

wardly diverging position, a vertically movable horizontal plate narrower than the space between said tracks and normally located below the tracks a distance greater than the thickness of said brick, means at one side of the tracks adapted to push a brick laterally onto said plate, and means for raising the plate to lift a brick thereon up between the diverging flanges high enough to lift them out of engagement with said tracks, whereby the flanges will spring inwardly against the sides of the brick so that said plate can lower the encased brick between the tracks.

12. Apparatus for applying a channel shape sheet metal case with downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, means for pushing a case lengthwise onto said tracks to spring the case flanges outwardly into downwardly diverging position, a vertically movable horizontal hold-down plate, rollers mounted in said plate and adapted to engage the top of a case on said tracks, springs pressing said plate downwardly, and means adapted to lift a refractory brick up between the diverging flanges high enough to raise said plate and to lift the case out of engagement with said tracks, whereby the case flanges will spring inwardly against the sides of the brick and the encased brick can be lowered between the tracks.

13. Apparatus for applying a channel shape sheet metal case with downwardly extending flanges to a refractory brick that is wider than the space between the lower edges of the flanges, comprising a box provided with substantially parallel side walls and an open end and bottom, a pair of tracks in the box mounted on the lower portions of its side walls and adapted to support the lower edges of the flanges of a case and to project a short distance up into it, said tracks being spaced apart farther than the upper portions of the case flanges, means for pushing a case lengthwise onto said open end of the box and along said tracks to spring the case flanges outwardly into downwardly diverging position, means adapted to lift a refractory brick up between the diverging flanges high enough to lift them out of engagement with said tracks, whereby the flanges will spring inwardly against the sides of the brick and the encased brick can be lowered between the tracks, the side walls of the box being provided with openings above said tracks, centering members slidably mounted in said openings and adapted to engage said diverging flanges, and springs pressing said members inwardly to center the case between the side walls when the case flanges are released from the tracks.

14. Apparatus for applying a channel shape sheet metal case with downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, a hopper for receiving a stack of such cases, a reciprocating pusher for pushing the bottom case of the stack lengthwise from said hopper forward onto said tracks to spring the case flanges out-

wardly into downwardly diverging position, said pusher having an elevated table portion extending rearwardly for holding up the rest of the cases while the bottom case is being pushed forward, and means adapted to lift a refractory brick up between said diverging case flanges high enough to lift them out of engagement with said tracks, whereby the flanges will spring inwardly against the sides of the brick and the encased brick can be lowered between the tracks.

15. Apparatus for applying a channel shape sheet metal case with downwardly extending flanges to a refractory brick that is wider than the space between the lower edges of the flanges, comprising a pair of substantially parallel tracks adapted to support the lower edges of the flanges of such a case and to project a short distance up into it, said tracks being spaced apart farther than the upper portions of the case flanges, a hopper spaced from one end of the tracks for receiving a stack of such cases, tracks at the bottom of the hopper adapted to support the lower edges of the bottom case in the stack, guide

tracks adapted to engage the inside of the case flanges and support their lower edges, the guide tracks diverging from the hopper tracks to said parallel tracks, a pusher in the bottom of the hopper reciprocable along the hopper tracks for pushing the bottom case of the stack from the hopper forward along the guide tracks to said parallel tracks where the case flanges are sprung outwardly into downwardly diverging position, 10 said pusher having an elevated table portion extending rearwardly for holding up the rest of the cases while the bottom case is being pushed out of the hopper, and means adapted to lift a refractory brick up between said diverging case flanges high enough to lift them out of engagement with said parallel tracks, whereby the flanges will spring inwardly against the sides of the brick and the encased brick can be lowered between the tracks.
